UNITED STATES PATENT OFFICE.

OWEN L. DAUTRICK, CLARENCE G. JOHNSON, AND ARTHUR KRASKA, OF DETROIT,
MICHIGAN, ASSIGNEES TO DAUTRICK JOHNSON MANUFACTURING COMPANY, OF
DETROIT, MICHIGAN, A CORPORATION OF MICHIGAN.

OVERHEAD DOOR.

Application filed October 16, 1922. Serial No. 594,725.

To all whom it may concern:

Be it known that we, OWEN L. DAUTRICK, CLARENCE G. JOHNSON, and ARTHUR KRASKA, citizens of the United States of America, residing at Detroit, in the county of Wayne and State of Michigan, have invented certain new and useful Improvements in Overhead Doors, of which the following is a specification, reference being had therein to the accompanying drawings.

This invention relates to sectional foldable doors, shutters or closures that may be advantageously used in connection with garages or other buildings having large or wide doorways; vehicles having bodies provided with openings; large file cases, and any structure having an opening that may be closed by a shiftable flexible or foldable door in contra-distinction to a hinged door or closure.

Our invention aims to provide garage door installations for units which may be assembled, in part, at a factory and shipped to the owner or builder of a garage to be easily and quickly installed to provide the garage with a door, which when closed, affords a safe and durable closure for the garage, and when open occupies an overhead position out of the road. The door is shiftable from a vertical position to a horizontal position and is counterbalanced so that it may be easily moved and safely left in any adjusted position. The counterbalance mechanism eliminates slamming and jarring of the door and insures an easy movement of the same after the door is unlocked, it being equipped with a locking mechanism that will prevent the door from being surreptitiously opened.

Our invention further aims to provide a sectional foldable door with novel pieces of hardware for guiding and supporting sections of the door when shifted, two of the pieces of hardware automatically causing a section of the door to assume a closed position and cooperate with other sections of the door in providing practically an air tight closure for the doorway.

The construction entering into our invention will be hereinafter specifically described and then claimed, and reference will now be had to the drawings, wherein—

Figure 1 is an elevation of the inner side of a sectional foldable door in accordance

with our invention, showing part of the garage unit in cross section;

Fig. 2 is a horizontal sectional view taken on the line II—II of Fig. 1 parts being omitted;

Fig. 3 is a cross sectional view of the lock mechanism of the door taken on the line III—III of Fig. 1;

Fig. 4 is a vertical longitudinal sectional view of the door taken on the line IV—IV of Fig. 1;

Fig. 5 is a perspective view of a portion of the door and one of its guide rails;

Fig. 6 is an edge view of a portion of the door relative to a guide rail;

Fig. 7 is a vertical longitudinal sectional view, somewhat diagrammatic, of a door that may be shifted into an overhead closure or concealed by a ceiling, and

Fig. 8 is a similar view of a door that may be used in connection with a delivery wagon, freight car or other vehicle.

In the drawings, the reference numeral 1 denotes a wall having a doorway 2 and this wall may be considered as part of a garage which has another wall, overhead beam, roof member or other support 3 approximately in a horizontal plane with the lintel or upper edge of the doorway 2, and while the wall 1 and its doorway 2 may be common to various structures, it may be necessary to provide the support 3.

Our sectional foldable door unit includes two side frames, each comprising a vertical member 4, a horizontal member 5 and a brace or fillet 6 at the juncture of said member which are placed at a right angle to each other and when erected afford an inverted L-shape frame between the wall 1 and the support 3 with the members 4 and 5 suitably secured to the wall 1 and the support 3 contiguous to the doorway 2.

Suitably secured to the confronting walls of the side frames are angle rails 7 extending throughout the length of said frames, that is, from the lower ends of the members 4 upwardly and inwardly to the ends of the members 5, the rails 7 having curved portions 8 on the braces 6. These rails are preferably made of angle bars with projecting flanges thereof serving as a track and other flanges as means of anchoring the rails to the side frames.

The sectional foldable door comprises a

bottom panel 9 intermediate panels 10 and 11 and a top panel 12, said panels having the adjoining edges thereof, at the inner side of the door, hinged together, as at 13, so that the door may have its panels swing to one side of the vertical planes. The door panels are of sufficient area to close the doorway 2 and overlap the edges of said doorway, and assuming that the door closes the doorway, as shown in Figs. 1 and 4, it is adapted to be raised and shifted to a horizontal position as indicated by full lines and dotted lines in Fig. 4.

Considering the hardware for the door, the panels 9, 10 and 11, adjacent the upper edges thereof and at their ends, are provided with angle brackets 14 projecting inwardly from the inner faces of said panels. These brackets are provided with anti-frictional rollers 15 and 16, the latter being flanged and both of said rollers engaging opposite faces of the rails 7, as best shown in Fig. 2. With the rails 7 properly positioned the rollers 15 and 16 and the brackets 14 will movably hold the door against the wall 1 and the flanges on the rollers 16 will prevent the brackets 14 from contacting with the rails 7. The brackets 14 and the rollers thereof constitute retaining members for at all times retaining the door panels in engagement with the rails 7 particularly when said door is being shifted.

The top panel 12 may have windows or lights 17 and on the ends of said panel, adjacent the upper edge thereof, are angle brackets 18 to which are pivotally connected links 19 supporting roller carriers 20 having anti-frictional rollers 21 engaging the rails 7 similar to the rollers 15 and 16. The roller carriers 20 have stops 22 adapted to engage stop brackets 23 on the braces 6 and the links 19 have supporting members or lugs 24 adapted to be engaged by the top panel 12 when in a horizontal position, as best shown in Fig. 4. The roller carriers 20 and links 19 cooperate with the curved portions 8 of the rails 7 in causing the top panel 12 to swing to a closed position against the door jamb as the door is lowered and closed. This is brought about by the stops 22 of the roller carriers engaging the stop brackets 23, said stop brackets defining the position of the roller carriers relative to the rails so that the links 19 will force the ends of the top panel 12 against the wall 1 or the door jamb. As the door is raised the roller carriers following the rails 7 will cause the top panel 12 to swing away from the wall 1 and gradually assume a horizontal position relative to the members 5. As the top panel assumes this position it comes to rest on the supports or lugs 24 and since the top panel 12 is hinged to the intermediate panel 11, said top panel will be safely supported in its horizontal or overhead position.

On the ends of the bottom panel 9, adjacent its lower edge, are pieces of hardware comprising angle brackets 25 provided with rail engaging rollers 26 and wall or jamb engaging rollers 27, the ends of the panel 70 being cut away as at 28, to provide clearance for the rollers 27 so that said rollers may contact with the wall 1 or door jamb instead of the ends of the panel. Otherwise, when the door is being shifted from a horizontal 75 position to a vertical position the ends of the panel would strike the wall and in all probability be injured thereby.

Mounted on the side frames and projecting upwardly from the upper ends of the members 4 are other pieces of hardware, comprising angle brackets 29 provided with bearings 30 for rotatable sheaves or pulleys 31 over which extend cables or flexible members 32 having the lower ends thereof attached, as at 33, to the angle brackets 25 of the bottom panel 9. The lower ends of the cables 32 are at times, between the members 4 and the ends of the door panels, and the upper ends of the cables are looped and attached to the angle brackets 29 by nut equipped eye bolts 34 or other fastening means. Engaging the looped portions of the cables 32 are sheaves or pulleys 35, carried by stirrups or yokes 36 attached to coiled retractile springs 37 extending to the support 3 where said springs are attached to the support by screw eyes 38 or other fastening means. It is obvious that turn buckles or suitable take-up devices may be associated with the springs 37 and the cables 32 to increase or decrease the tension or length of such members.

The inner sides of the panels 9 and 10, at the lower edges thereof, have suitable handles 39 and the panel 10 is provided with a door locking mechanism including slide bars 40 movable in guides 41 at the ends of the panel 10 and adapted to extend into keeper plates 42, carried by the confronting walls of the members 4. The inner ends of the bars 40 are offset and pivotally connected, as at 43, to a turn member 44 mounted on a spindle 45 provided with inside and outside handles 46. The spindle 45 is journaled in a bearing 47, carried by the panel 10, and the turn member 44 has a notch 48 to receive a bolt 49 forming part of a lock mechanism 50 carried by the panel 10. The lock mechanism 50 is of a well known make and key operated from the outer side of the door.

Suitably attached to the members 4 are the ends of a cable or flexible member 51 which engages rollers or sheaves 52 at the lower edge of the bottom panel 9, said cable or flexible member extending crosswise of the panel at the inner side thereof so that it may be readily gripped to facilitate lowering and closing the door from a horizontal 100

or open position. Since the ends of the cable are attached to the members 4 and can be easily gripped it is obvious that the door can be pulled downwardly from its 5 overhead position.

As shown in Fig. 7 the sectional foldable door may be shifted into a compartment 53 above a ceiling 54 whereby the door when opened is invisible.

10 As shown in Fig. 8 the door may be used to close an opening 55 in the body 56 of a vehicle in which case we substitute elastic cords or members 57 for the springs 37, because the vehicle door may be smaller and 15 lighter in weight than a garage door.

What we claim is:—

1. A door installation for a building having a doorway, comprising inverted L-shaped side units adapted to be mounted at the sides 20 of the building doorway, each unit including a horizontal member longer than the height of the door-way, rails carried by the confronting sides of said units, a sectional foldable door slidable on said rails and 25 adapted to close said doorway and when open occupy a horizontal overhead position above the horizontal plane of the horizontal members of said units, and a counterbalance for said door extending above and along the 30 horizontal member of each unit.

2. A door installation as called for in claim 1, wherein the counterbalance for the door includes flexible members having lower ends thereof held by said door and upper 35 loop ends attached to said side units, pulleys engaging the loop ends of said flexible members, and coiled springs attached to said pulleys and held at the rear ends of the horizontal members of said units.

40 3. A door installation for a building having a doorway and a support adjacent said doorway, comprising side units mounted between said doorway and said support, each side unit composed of a horizontal member 45 attached to said support and a vertical member at said doorway, a sectional foldable door slidably supported from said side units and adapted when closed to occupy a ver-

tical position at said doorway and when open occupy a horizontal position between said doorway and said support above the horizontal plane of the horizontal members of said units, and a counterbalance for said door adapted to hold said door at any position to which it may be shifted, said counterbalance being one for each unit with each counterbalance attached to said support and extending forwardly above the horizontal member of each unit. 50

4. A door installation as called for in claim 3, wherein said counterbalance includes flexible members attached to said door and having looped portions at said side units, pulleys in the looped portions of said flexible members, and springs connecting said pulleys to said support. 60

5. The combination of a wall having a doorway, a door for such doorway composed of hinged panels, rails adapted to guide said door from a vertical position at said doorway to an overhead horizontal position, carriers on said rails adapted to have the uppermost door panel rest thereon when in an overhead horizontal position, and links connecting said carriers to the uppermost panel 70 of said door, said links cooperating with other panels of said door, said carriers and said rails in supporting the uppermost panel 75 when in an overhead position.

6. The combination called for in claim 5, and means adjacent said rails adapted to be engaged by said carriers to cause said carriers to assume positions at right angles to said door and said links to close the uppermost door panel against said wall and 80 cooperate with said means, rails and carriers in bracing the door panel. 85
